CLARENCE J. KLEIN, OF BELLEVUE, PENNSYLVANIA, ASSIGNOR TO UNITED ENGINEERING & FOUNDRY COMPANY, OF PITTSBURGH, PENNSYLVANIA, A CORPORATION OF PENNSYLVANIA

CONTROL MECHANISM

Application filed May 15, 1928. Serial No. 277,976.

The present invention relates broadly to the art of machine controls, and more particularly to an improved form of control mechanism particularly useful, for example, in the 5 metal working industries for the control of reels, such as cold strip reels.

It is desirable in the operation of reels to be able to stop the same at a certain predetermined point to permit the entry of the leading end of a strip of material from the mill into the same at the commencement of a coiling operation. Most of the coils in use at the present time are of the well-known collapsible type having a limited rotational movement 10 with respect to the driving shaft, as well understood in the art, the construction being such that the inertia of the coiled mass carries the same sufficiently in advance of the driving mechanism upon stoppage of such 15 mechanism as to insure collapsing of the reel to facilitate stripping.

The present invention is not concerned with the construction of the reel, it being adapted 20 for use with any reel of the general type referred to, as will be more apparent as the operation of the control mechanism becomes better understood.

In the accompanying drawings I have 25 shown by way of illustration only, a certain preferred embodiment of my invention. Changes in the construction and arrangement 30 of the parts, in the type and construction of the reel, and in the type and manner of operation of the various switches, circuits and 35 control operation may be made without departing from the spirit of the invention or the scope of my broader claims.

In the drawings:—

Figure 1 is a side elevation of a control 40 mechanism constructed in accordance with the present invention.

Figure 2 is a top plan view of the mechanism of Figure 1, the housing cover for the 45 gears being removed for purposes of illustration.

Figure 3 is a longitudinal sectional view through a portion of the driving mechanism.

Figure 4 is a sectional view on the line 50 IV—IV of Figure 1, looking in the direction of the arrows.

Figure 5 is a detail elevational view, on an enlarged scale, of a portion of the adjustable driving mechanism.

Figure 6 is a diagrammatic layout of the 55 control mechanism, and

Figure 7 is a side elevational view of a portion of such mechanism.

The control mechanism herein illustrated 60 comprises a suitable base 2, having mounted thereon a driving motor 3, effective through the gear train 4, for driving a sleeve 5, surrounding a reel driving shaft 6, and mounted as clearly indicated in Figure 3 of the drawings.

Secured to the sleeve for rotation therewith 65 is a cone clutch member 7, within which is disposed a similarly shaped combined clutch and braking member 8. The combined clutch and braking member is splined to the reduced end 9 of the shaft 6, in such manner as to rotate therewith while permitting movement axially thereof. The member 8 is faced on opposite sides thereof, the facing 10 being provided for engagement with the clutch 7, 70 while the facing 11 is provided for engagement with a stationarily mounted brake member 12, carried by the frame 13, of the machine, which in turn is secured to the base.

The shaft 6 is provided beyond the reduced 75 portion 9 with an extension 14, around which is positioned a compression spring 15, guided at its inner end by the reduced portion 9 which it surrounds, as clearly indicated in Figure 3, and abutting at this end against a collar 16 on the member 8. At its opposite end it abuts against a follower 17, held in 80 adjusted position by nuts 18. It will be apparent that this construction is such that the

spring 15 is normally effective for urging 85 members 7 and 8 into driving relationship so that the motor 3 will effect rotation of the shaft 6. This shaft at its outer end carries a suitable reel 19, indicated in broken lines, and of any type having a relative movement with respect to the shaft for accomplishing 90 collapsing thereof in the manner referred to when the shaft is stopped.

Also carried by the frame 13 is a pivot 20, on which is mounted a lever 21. At an intermediate point in its length, the lever is pro- 100

vided with projections 22, extending into a groove 23, in the collar 16. The lower end of the lever 21 has a pivotal connection 24, with a piston rod 25, in the cylinder 26. The cylinder 26 has communicating therewith a pressure supply line 27, leading to a control valve 28, as indicated in Figures 2 and 6. Upon the supply of fluid under pressure through the line 27, it will be apparent that the piston 25 is moved to the right, as viewed in Figure 1 of the drawings, thereby rocking the lever 21 in a counter-clockwise direction about the pivot 20. This moves the collar 16 to the right, as viewed in Figure 3 of the drawings, thereby compressing the spring 15 and moving the combined clutch and brake member 8 in such manner as to bring the surface 11 into contact with the brake 12, to stop rotation of the shaft 6. It will be apparent that this movement of the member 8 automatically effects disengagement thereof from the clutch 7, so that the driving influence of the motor 3 is no longer transmitted by the sleeve 5 to the shaft 6. Upon the exhaust of fluid from the cylinder 26, through the line 27, the spring will again force the members 7 and 8 into engagement and establish a driving connection.

For determining the maximum power transmission through the frictional drive established by the members 7 and 8, there is provided a hand wheel 29, carried by a rod 30, having a pivotal connection 31 with the upper end of the lever 21. By adjusting the hand wheel in one direction or the other, the lever 21 may be rocked in the desired direction for either decreasing the effective action of the spring 15, or increasing its efficiency. This enables the frictional drive to be carefully and accurately adjusted.

When the driving mechanism is stopped, it is desirable for the reasons hereinbefore pointed out, to stop the same at a predetermined point so as to insure positioning of the reel in a manner to facilitate entry of the leading end of the oncoming material to be coiled. For obtaining the desired action in this respect, I provide the extension 14, as indicated diagrammatically in Figure 6, with a spring arm 32 of generally U-shape. One end of the U is secured to the extension 14, and the opposite end carries a projection 33, adapted to be engaged at will with any one of the slots 34 in the periphery of a driving disk 35. The disk 35 is secured to a shaft 36, on which is mounted a rotating contactor 37. The main body of this contactor, as indicated in Figure 7 of the drawings, is of non-conducting material, electrically, but is provided with a conducting segment 38 at one point in its periphery. This segment once in each revolution of the contactor passes under the free ends of brushes 38^a. One of these brushes has a connection 39, with a line wire L constituting one side of a source of elec-

trical energy, the other brush having a connection 40 to the terminal 41 of a stop-switch 42. The terminal 43 of the stop-switch has a connection 44 to a terminal 45 of a solenoid 46. The other terminal 47 of this solenoid has a connection 48 to line wire L', constituting the other side of a source of electrical energy. With this construction, it will be apparent that upon closing the stop-switch 42, a potential circuit will be completed with the solenoid 46, which circuit is energized, however, only when the segment 38 of the contactor 37 passes under both of the brushes 38^a.

This is true for the reason that the brushes 38 are in series in the circuit of the solenoid 46 with the stop-switch, thereby requiring simultaneous closing both of the stop-switch and of the circuit including the brushes 38^a before the solenoid 46 will be energized.

Upon completion of the solenoid circuit, this solenoid, which may be designated the stop solenoid, will move the piston 49 in the control valve 28 to the left, as viewed in Figure 6, thereby bringing the pressure supply line 50 into communication around the piston with the line 27 to supply actuating fluid to the brake cylinder 26. This will in turn disengage the members 7 and 8 as described, and cause the members 8 and 12 to engage. By properly adjusting the relationship between the disk 35 and the extension 14 through the medium of the projection 33 and the slots 34, the exact point of stoppage of the driving mechanism may be controlled.

In order to effect an emergency stop of the apparatus instantly, in case such an operation is required, there is provided an emergency stop-switch 51, having its terminal 52 provided with a connection 53 leading to the line wire L, and having its terminal 54 provided with a connection 55, leading to the connection 44. It will be apparent that this switch when closed is effective for short-circuiting the portion of the circuit including the limit switch brushes 38^a, thereby enabling the stop solenoid 46 to be energized instantly by the mere act of closing the emergency stop-switch 51.

In order to effect such a movement of the piston 49 in the valve casing 28, as will exhaust the line 27, there is provided a rotating switch 56, having its terminal 57 provided with a connection 58, to the line wire L, and its terminal 59 provided with a connection 60 to one terminal 61 of the rotating solenoid 62. The other terminal 63 of this solenoid has a connection 64 to the wire 48 connected to the line wire L'.

Thus, upon closing the rotating switch 56, the solenoid 62 will be energized, and the piston 49 moved into the position indicated in dotted lines in Figure 6. In this position, the line 27 will be open to exhaust, and the line 50 will be cut off from supplying any

fluid. With the parts in this position, the spring 15 will move the members 7 and 8 into engagement for effecting a driving operation of the shaft 6 and the reel carried thereby.

5 It will be apparent from the foregoing that I have provided a combined control and driving mechanism, including a member movable in opposite directions, for effecting a driving engagement upon movement in one direction, 10 and braking engagement upon movement in the opposite direction. I also provide an adjustment whereby the efficiency of the frictional drive connection may be varied at will.

The character of the operation of the combined clutch and braking member is controlled normally by separate switches actuating a solenoid controlled valve, the system including means for effecting an emergency stop at any time. Under normal conditions, 15 the circuit includes a limit switch insuring stoppage at a predetermined position. The limit switch and mechanism are adjustably interconnected whereby this relationship can be varied, as may be found necessary or desirable.

25 I claim:—

1. The combination with a reel driving shaft, of means for driving said shaft, means for checking the rotation of said shaft, means 30 operable at will for stopping said shaft at any time, and other means effective for stopping said shaft only in predetermined position.

2. A control mechanism, including a shaft, 35 shaft driving means, shaft braking means, a limit switch operable in timed relation with said shaft, and means for adjusting the relationship between said shaft and said limit switch.

40 3. A control mechanism, including a shaft, shaft driving means, shaft braking means, a limit switch operable in timed relation with said shaft, means for adjusting the relationship between said shaft and said limit switch, 45 and means in circuit with said limit switch for manually closing the circuit thereto and effecting operation of said braking means.

4. In a control mechanism, a brake, a clutch, a limit switch rotatable in timed relation to said clutch, and solenoid operated control means for said clutch and brake.

50 5. The combination with a reel, of driving mechanism, braking mechanism, means for rendering said braking mechanism effective 55 at any time, and other means operative for rendering said braking means effective only at predetermined times.

In testimony whereof I have hereunto set my hand.

CLARENCE J. KLEIN.
